UNITED STATES PATENT OFFICE

LEON O. CORELL, OF KALAMAZOO, MICHIGAN, ASSIGNOR TO THE WIGGINTON COMPANY, OF KALAMAZOO, MICHIGAN

DOOR-OPERATING MECHANISM

Application filed August 24, 1928. Serial No. 301,883.

The main objects of this invention are:

First, to provide in a door operating mechanism an improved control means for the motor by means of which a reversing motor is automatically adjusted so that on successive actuations of a push button or control switch, the door is operated in opposite directions.

Second, to provide in a door operating mechanism a brake means by which the momentum of the parts is effectively checked without injury or shock.

Third, to provide an improved door operating mechanism in which the parts are arranged so that the strain thereon is minimized and the parts are simple and durable.

Objects relating to details and economies of my invention will appear from the description to follow. The invention is defined and pointed out in the claims.

20 A structure which is a preferred embodiment of my invention is illustrated in the accompanying drawing, in which:

Fig. 1 is a detail plan view of my door operating mechanism shown in operative relation to a pair of hinged doors.

Fig. 2 is a fragmentary plan view with the mechanism actuated to open the doors.

Fig. 3 is a fragmentary side elevation of the main operating parts.

20 Fig. 4 is a fragmentary view partially in vertical longitudinal section on a line corresponding to line 4—4 of Figs. 5, 6 and 7.

Fig. 5 is a detail view partially in horizontal section on line 5—5 of Fig. 6.

35 Fig. 6 is a detail view partially in transverse section on line 6—6 of Figs. 3, 4 and 5.

Fig. 7 is a fragmentary section corresponding to that of Fig. 6 with the running switch open.

40 Fig. 8 is a diagrammatic view showing the relation of the running and starting switches to the motor.

In the drawings similar reference characters refer to similar parts throughout the several views.

Referring to the drawings, 1, 1 represent the doors to be controlled which are hinged at 2. The mechanism is mounted on elevated supports 3 disposed in parallel relation to the doors when closed. When the mechanism is

used for operating a sliding door the mechanism is disposed in parallel relation thereto and the connections modified accordingly.

A channeled slideway 4 for the rack 5 which is the actuated element of the mechanism is mounted on the supports 3. This slideway also constitutes a support for the bed member or bracket 6 on which the motor 7 is mounted. This motor is a reversible motor, the reversing element being indicated at 8—see Fig. 4.

A pin 9 projects from this reversing element through a slot 10 in the motor housing, a spring 11 coacting with the pin for yieldingly holding the reversing element at the ends of its stroke.

The shaft 12 of the motor is provided with a pinion 13 meshing with a gear 14 on the driven shaft 15. This shaft 15 is provided with a pinion 16 meshing with the rack. The gear 14 is connected to the shaft by means of a friction driving connection consisting of the disc 17 splined to the shaft and having a friction face 18 coacting with the side of the hub 19 of the gear, a thumb screw 20 being provided to regulate the driving friction.

On the shaft 15 I mount a brake drum 21. The coacting brake shoes 22 are mounted on opposite sides of the shaft 15. These brake shoes are of segmental shape and are pivotally mounted at 23 on the arms 24 which are supported in the brackets 25 for reciprocating and tilting movement. The released position of the brake shoes is shown by full lines in Fig. 3 in which position the upper portions of the brake shoes rest on the drum.

The actuated position of one of the brake shoes is indicated by dotted lines in Fig. 3. Thrust springs 26 are mounted on the arms with one end in engagement with the bracket 27 and the other end engaging pins 28 on the arms. These springs are placed under compression when the brake shoes are in actuated position and yieldingly support them against the drum.

The brake shoes are held in released or in inoperative position by means of the sliding detents 28 which are arranged in suitable ways disposed transversely of the rack, the detents being provided with beveled or 100

cammed ends 29 adapted to be engaged by the rack for forcing the detents to arm engaging position so that the rack acts to hold both detents in brake releasing position until the travel of the rack is such as to release 5 one of the detents, allowing its releasing spring 30 to disengage the same.

The brake shoe being in frictional contact with the drum, the friction of the drum on the brake shoe will carry the brake shoe downwardly and owing to the pressure of the spring 26 thereon, the brake is actuated into clutching engagement with the drum. However, on rotation of the drum in the opposite direction, the brake is automatically returned 15 to released position and as soon as the rack begins its travel, the detent is actuated to hold the brake in released position. The travel of the rack to the opposite ends of its stroke will 20 release the brake, allowing it to act as described.

The reversing member of the motor is automatically reversed on each stroke of the rack by means of the tappet 31 carried by the 25 rack and coacting with the pin 9 on the reversing member. This tappet is pivoted at 32 and is held yieldingly in central upright position by means of the springs 33 which are of sufficient strength to overcome the 30 springs 11 and shift the reversing member, however allowing the tappet to pass under the pin when the end of the slot 10 is reached so that the tappet is in position to engage the 35 opposite side of the pin and shift it in the opposite direction on the movement of the rack in the opposite direction.

The rack also controls the running switch designated generally by the numeral 34 and consisting of a pair of electrically connected 40 contacts 35 and a pair of switch members 36 connected in the circuit 37 by the lead wires 38. These switches 36 are supported by spring arms 39 adapted to automatically open the switch members when the arms are 45 released. These arms are provided with tappets 40 projecting through openings 41 in the bottom of the slideway to be engaged by the rack and held in closed position thereby until the rack reaches the end of its travel 50 when one of the switch members 39 is released thereby opening the running switch and stopping the motor. This occurs at approximately the same time as the releasing of one of the brake detents.

55 The control or starting switch 42 (see diagram Fig. 8) is also connected in the circuit 37 as by means of the lead wires 43. The closing of this switch 42 starts the motor and it should be held closed until the movement 60 of the rack has closed the running switch. The starting or control switch may then be released. The running switch is held closed by the rack until it reaches the end of its travel in the particular direction it may be 65 moving.

The reversing tappet is positioned so that the reversing member is actuated during the travel of the rack or before the opening of the running switch so that on succeeding actuations of the starting switch the rotor will 70 travel in opposite directions.

By this arrangement of parts, the brakes act to check the momentum of the parts without undue stress or shock thereto and the mechanism is simple and durable. The control 75 is also simple and durable.

I have illustrated and described my improvements in an embodiment which I have found very practical. I have not attempted to illustrate other modifications and adaptations as it is believed this disclosure will enable those skilled in the art to embody or adapt my improvements as may be desired. 80

Having thus described my invention, what I claim as new and desire to secure by Letters 85 Patent, is:

1. In apparatus of the class described, the combination with a motor, of a driven rack, driving connections for said rack to said motor provided with a brake drum, oppositely disposed brake shoe arms mounted on opposite sides of the axis of said drum for reciprocating and swinging movement, brake shoes pivotally mounted on said arms so that their upper portions rest on said drum when in released position, thrust springs for 90 said brake shoes, detents coacting with said brake shoe arms for holding said brake shoes in released position, springs acting to urge said detents to releasing position and project them into the path of said rack, said rack acting to move said detents to and retain them in actuated position, a running switch for said motor controlled by said rack, and a starting switch for said motor. 95

2. In an apparatus of the class described, the combination with a motor, of a driven rack, driving connections for said rack to said motor provided with a brake drum, oppositely disposed brake shoe arms mounted on opposite sides of the axis of said drum for reciprocating and swinging movement, brake shoes pivotally mounted on said arms so that their upper portions rest on said drum when in released position, thrust springs for 100 said brake shoes, detents coacting with said brake shoe arms for holding said brake shoes in released position, and springs acting to urge said detents to releasing position and project them into the path of said rack, said rack acting to move said detents to and retain them in actuated position. 105

3. In an apparatus of the class described, the combination with a motor, of a reciprocating driven element, driving connections for said motor to said driven element provided with a brake drum, brake shoe arms mounted on opposite sides of the axis of said brake drum for reciprocating and swinging movement, brake shoes mounted on said arms 110

so that their upper ends rest on said drum when in released position, thrust springs for said brake shoes, and spring released detents coacting with said brake shoe arms and 5 operatively associated with said driven element which acts to shift said detents to and retain them in actuated position.

4. In an apparatus of the class described, the combination of a motor, a driven element, 10 driving connections for said motor to said driven element provided with a brake mechanism comprising a brake drum, brake shoes mounted on opposite sides of the axis of said brake drum for pivotal, swinging and reciprocating movement, thrust springs acting 15 to yieldingly urge said brake shoes into engagement with said drum, spring released detents adapted to hold said brake shoes in released position with portions thereof in contact with said drum, said detents being controlled by and held in actuated position by said driven element, a running switch for said motor controlled by said driven element, and a starting switch for said motor.

25 5. In an apparatus of the class described, the combination of a motor, a driven element, driving connections for said motor to said driven element provided with a brake mechanism comprising a brake drum, brake shoes 30 mounted on opposite sides of the axis of said brake drum for pivotal, swinging and reciprocating movement, thrust springs acting to yieldingly urge said brake shoes into engagement with said drum, and spring released 35 detents adapted to hold said brake shoes in released position with portions thereof in contact with said drum, said detents being controlled by and held in actuated position by said driven element.

40 6. In an apparatus of the class described, the combination of a motor, a driven element, driving connections for said motor to said driven element provided with a brake including a brake drum, brake shoes mounted on 45 opposite sides of the axis of said brake drum, detents adapted to hold said brake shoes in released position with portions thereof in contact with said drum, said detents being controlled by and held in actuated position 50 by said driven element, a running switch for said motor controlled by said driven element, and a starting switch for said motor.

55 7. In an apparatus of the class described, the combination of a motor, a driven element, driving connections for said motor to said driven element provided with a brake including a brake drum, brake shoes mounted on opposite sides of the axis of said brake drum, and detents adapted to hold said brake shoes 60 in released position with portions thereof in contact with said drum, said detents being controlled by and held in actuated position by said driven element.

65 8. In an apparatus of the class described, the combination with a motor, of a driven

element, driving connections therefor to said motor provided with a brake drum, brake shoes mounted for pivotal and swinging movement on opposite sides of the axis of said brake drum and so that portions thereof 70 are in contact with said drum when in released position, means for holding said brake shoes in released position controlled by said driven element, said means being actuated to alternately release said brake shoes, and a 75 motor control means including said driven element.

In witness whereof I have hereunto set my hand.

LEON O. CORELL.
